UNITED STATES PATENT OFFICE.

OTTO WEEBER, OF BERLIN, GERMANY, ASSIGNOR TO SIEMENS & HALSKE AKTIENGESELLSCHAFT, WERNERWERK, OF SIEMENSSTADT, NEAR BERLIN, GERMANY.

HAND TELEPHONE.

Application filed September 11, 1925, Serial No 55,651, and in Germany January 22, 1925.

In the hand telephones known heretofore the cover of the casing formed as an ear-piece and in which the microphone and the telephone are located have been either screwed 5 to the casing or attached thereto by means of a bayonet socket. Thus, the cover can be freed straight-way or by means of a screw-driver, consequently damage can easily be done to the apparatus contained inside the 10 casing because the parts are very sensitive, and even a slight variation of their position causes considerable effect on their mode of operation.

The invention now aims at making it impossible, or at least difficult for unauthorized persons to loose the cover from the casing, this being attained according to the invention by the cover and its casing being connected by locking members arranged in the interior 20 of the casing, these members only being accessible with the aid of a special tool which enables them to be brought out of their locking position.

According to the invention the locking fastening devices are preferably formed as flat 25 springs. It is of advantage to use the same springs which bring about the conductive connection from the cap-shaped telephone or microphone to the connecting cord of the instrument.

The invention is also directed to the special formation of these contact springs, of which one presses in an axial direction against the central pole arranged at the base of the case, the latter pressing against a stop of the cover, 35 whilst the other contact spring exerts a pressure on the case from opposite sides in a radial direction.

The invention now describes more closely 40 in an actual example which is shown in Fig. 1 in side elevation with the telephone casing in section whilst Fig. 2 represents the open casing in plan with the telephone case removed.

In the example shown the handle 1 together with the casings 2 and 3 are made of one piece of compressed insulating material. The latter is preferably of hard rubber or 45 phenol composition because, when this is used, the hand telephone is given considerable strength as well as a very light weight. The telephone 4 and also the microphone are both formed as cylindrical units, but the drawing only shows the telephone 4. The units are loosely arranged in the casings 2 and 3 and

have their top portions lying against a stop 5 of the cover 6 or 7. The conductive connection from the case or from the central, outwardly directed pole, to the cord (not shown) takes place over the contact springs 8 and 9 at 60 the bottom of the casings 2 and 3. One contact spring 8 has several arms 10 and 11 bent U shaped, two of these arms 11 having their bent ends pressing from opposite sides in a radial direction against the case 4, thus forming a contact with the case of the microphone which is constructed as a pole. The other two arms 10 are provided with catches 12 which are normally tensioned against the inner edge 65 of the covers 6 and 7 which are preferably of insulating material. In this manner the covers are secured to their casings.

The contact spring 8 is only attached to the base of its casing by means of a screw 13. In order to prevent a turning of the 75 spring 8 openings 14 are provided in the rim of the casing, the bent portions of the arms 10 and 11 fitting in these. The other contact spring 9 of the casings 2 and 3 is arranged transverse to the spring 8 and has its slotted, 80 upwardly bent end 15 lying in an axial direction against the central pole 16 which is located at the base of the microphone unit. The units are thus firmly pressed against an 85 annular boss 5 on the inner wall of the closing cover 6 or 7. In this manner the air-space between the diaphragms of the units and the closing covers is restricted laterally on and underneath the case, hence sound waves cannot be absorbed by this space and 90 weaken the effects of the apparatus.

In the embodiment shown four arms are provided on the contact spring, two of them making contact with the cases, whilst the others are used for holding the cover. The 95 arrangement can of course be so made by suitably shaping the spring 8 that the same arms serve for both purposes. As will be seen the arrangement described allows the covers to be placed on the casings without the 100 use of a special tool. If, however, the covers are to be removed from the casings, it is necessary to lift the catches 12 of the spring 8 from the inner rim of the covers. For this purpose openings 17 are provided in the covers at opposite points and serve for the insertion of two ends of a special tool, preferably made of a wire strip. The cover is now rotated by means of the inserted tool so that the openings 17 come to lie opposite the 110

catches 12 and the spring 8, whereupon the catches can be pressed inwards by means of the wire ends of the tool and the cover can be moved without further difficulty.

5. What is claimed is:

1. In a hand telephone, a receiver unit having terminals, a casing for receiving said unit, a cover for said casing to hold said unit in place, an element fastened to said casing, 10 means projecting from said element for making electrical contact with one terminal of said unit and additional means projecting from said element for holding said cover in place, said cover being held in place only by 15 said additional means.

2. In a hand telephone, a receiver casing, a receiver unit, a cover for said casing engaging said unit to hold it in place in the casing, a conductive element secured to the 20 face of the casing and having a plurality of arms extending upward therefrom, certain of said arms engaging the outer wall of said unit to form an electrical contact therewith and other of said arms having means associated therewith for locking said cover in 25 place.

3. In a hand telephone set, a casing carrying conductive elements, a unit for said casing having terminals engaging said elements 30 when the unit is placed in said casing, a cover for said casing, means on said cover co-

operating with one of said conductive elements to hold the cover in place, and additional means on said cover cooperating with another element to hold said unit in place. 35

4. In a hand telephone, a casing for receiving a receiver unit, a conductive element having extensions and secured to the base of said casing by a single screw, projections extending from the inner periphery of said casing to prevent rotary movement of said element, a cover for said casing and unit, said extensions of said conductive element and said cover cooperating to hold said casing, unit and cover together. 40 45

5. In a hand telephone, a telephone unit, a casing, a cover for said casing engaging said unit to hold it in place in the casing, a conductive element secured to the bottom of the casing and having a plurality of arms extending upwards therefrom, certain of said arms engaging the outer wall of said units to form an electric contact therewith, other of said arms locking said cover in place, and other conductive elements, said other conductive elements engaging the bottom of said unit to form an electrical contact therewith and to hold said unit tensioned against said cover. 50 55

In witness whereof, I hereunto subscribe my name this 20th day of August, A. D. 1925.

OTTO WEEBER.
